Primary Examiner—James Gandy*Assistant Examiner*—Stacia Sinuik**[57] CLAIM**

The ornamental design for a composite center casting for a wheel rim, as shown and described.

DESCRIPTION

FIG. 1 is a front perspective view of a composite center casting for a wheel rim showing my new design;

FIG. 2 is a front elevational view thereof;

FIG. 3 is a right side elevational view thereof, it being understood that the left side is the same as that shown;

FIG. 4 is a top plan view thereof; and,

FIG. 5 is a bottom plan view thereof.
